US00D962178S

(12) **United States Design Patent** (10) **Patent No.:** **US D962,178 S**
(45) **Date of Patent:** **** Aug. 30, 2022**

(54) **ELECTRICAL HOUSING**

(71) Applicant: **LEA ELECTRIC, LLC**, Boise, ID (US)

(72) Inventors: **Thomas T. Betty**, Boise, ID (US); **Alejandro R. Ybarra**, Boise, ID (US)

(73) Assignee: **LEA ELECTRIC, LLC**, Boise, ID (US)

(**) Term: **15 Years**

(21) Appl. No.: **29/713,205**

(22) Filed: **Nov. 14, 2019**

(51) **LOC (13) Cl.** **13-03**

(52) **U.S. Cl.**

USPC **D13/155**; D13/184

(57) **CLAIM**

The ornamental design for an electrical housing, as shown and described.

DESCRIPTION

FIG. 1 is an elevated perspective view of an electrical housing according to the present invention;

FIG. 2 is a rear elevated perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawing depict portions of the electrical housing that form no part of the claimed design.

1 Claim, 6 Drawing Sheets
